UNITED STATES PATENT OFFICE

ERNEST P. EVERETT, OF YONKERS, NEW YORK

HOOP FOR BARRELS AND OTHER CONTAINERS

Application filed September 15, 1926. Serial No. 135,510.

This invention relates to improvements in hoops for containers such as barrels, kegs, tubs and the like.

The invention proposes the use of commercial fibre board as a means for providing the body of a hoop. Fibre board as distinguished from wood, sheet metal and other materials heretofore used in the manufacture of hoops, is formed of vegetable pulp, or pulp mixed with other substances, and suitably processed, upon being turned into sheets, to render it tough. In point of hardness sheet fibre is about the same as medium hard wood, but it is more tough than any wood or sheet metal.

The properties of toughness and elasticity are highly desirable in any material to be used for container hoops; it being obvious that these properties combine to prevent displacement or creeping of the hoop after the same has been forced into position around the staves and thereby tensioned. When wood or metal is used for container hoops it is necessary to take into consideration the longitudinal flare of the staves and so shape the hoop that the inner face thereof will conform to the said flare. The usual practice adopted to meet this requirement is, in the case of a metal hoop, to form the same of a strip provided with concentric arcuate side edges, and in the case of a wooden hoop to bevel a face thereof. If a flat wooden or metallic hoop were constructed along cylindrical lines its lack of elastic properties would prohibit the hoop from conforming to the flare of the staves when forced around the same.

Coming now to the present invention the general object is to provide for imparting to a cylindrical hoop such of the properties of elasticity and toughness as will adapt the hoop to conform readily to the flare of a barrel, tub or the like when forced around the staves thereof.

The above and other objects are accomplished by instrumentalities pointed out in the following specification.

The invention is clearly defined in the claims.

A satisfactory embodiment of the invention is illustrated in the accompanying draw-

ings forming part of the specification and in which

Fig. 1 is a plan view of the blank of the present invention.

Fig. 2 is a perspective of the hoop formed from the blank of Fig. 1.

Fig. 3 is a side elevation of the upper end portion of a barrel showing the hoop of this invention applied thereto.

Fig. 4 is a perspective of a partly formed modified form of hoop.

Fig. 5 is a detail vertical cross section on the line 5—5 of Fig. 3, and

Fig. 6 is a detail cross section on the line 6—6 of Fig. 1.

In Fig. 1 of the drawings 5 designates a blank of fibre board of rectangular contour throughout. The length of blank 5 is such that when the end portions thereof are brought together, lapped and stapled as indicated by 6 a cylindrical hoop 7 is provided for suitably surrounding the staves of a container such as the barrel 8 shown in the drawings. It is of course to be understood that when the hoop is properly positioned upon the barrel as shown in Fig. 3 the inner marginal side portion thereof remote from the adjacent end of the barrel is expanded circumferentially and tensioned due to the slope of the staves while there is absence of tension in the opposite or outer edge of the hoop. As a consequence of this the inner side of the hoop slopes radially inward and bears upon the adjacent surfaces of the staves. In this way and by virtue of forming the hoop with an inside diameter approximately equal to the outside diameter of a section of the barrel disposed in the plane of the outer edge of the hoop, the elasticity of the material forming the hoop permits the same to readily conform to the longitudinal curvature of the barrel. It is to be noted that when the hoop is positioned around the barrel the tension is such as to prevent accidental creeping or displacement of the hoop. The hoop of course may be permanently fastened by any of the usual methods or by an adhesive coating disposed upon the inner face of the hoop.

In the modified form of the invention shown in Fig. 4 a hoop is formed by winding

a thin strip 9 of fibre upon a cylinder so as to provide a cylindrical hoop made up of a plurality of layers or laminations, 10 and 11, bearing one upon the other and permanently secured to one another by means of a coating of adhesive arranged therebetween. In this way there is provided a continuous cylindrical hoop formed of layers of fibrous material and adapted for conforming to the contour of a barrel or the like when forced thereon in the usual manner.

Although I have shown and described embodiments of my invention, it is to be understood that the same is susceptible of various changes, and I reserve the right to employ such of these as may come within the scope of the appended claims.

What I claim is:

1. A hoop, for flared containers, comprising a cylindrical body formed of fibre board and having sufficient inherent resiliency to permit the body to expand circumferentially and progressively from side to side in the application thereof to a container whereby the body conforms automatically to the flare of the container and tensionally embraces the same.

2. A hoop, for flared containers, comprising a cylindrical body of regular polygonal cross-section formed of fibre board and having sufficient inherent resiliency to permit the inner circumference of the body to expand progressively in the application of the body to a container whereby the said circumference is automatically conformable to the flare of the container and tensionably embraces the same.

3. A hoop, for flared containers, comprising a cylindrical body of rectangular cross-section formed of commercial artificial fibre board and having sufficient inherent resiliency to permit the inner circumference of the body to expand progressively in the application of the body to a container, whereby the said circumference is automatically conformable to the flare of the container and tensionably embraces the same.

4. A hoop, for flared containers, comprising a cylindrical body of rectangular cross-section formed of fibrous material made of vegetable pulp suitably processed to have sufficient toughness, elasticity, and inherent resiliency to permit the inner circumference of the body to expand progressively in the application of the body to a container, whereby the said circumference is automatically conformable to the flare of the container and tensionably embraces the same.

5. Signed at New York city, in the county of New York and State of New York, this 7th day of September, A. D. 1926.

ERNEST P. EVERETT.
